UNITED STATES PATENT OFFICE.

J. E. CROWELL, OF CHELSEA, MASSACHUSETTS.

MACHINERY FOR SPINNING YARN.

Specification of Letters Patent No. 28,161, dated May 8, 1860.

To all whom it may concern:

Be it known that I, J. E. CROWELL, of Chelsea, in the county of Suffolk and State of Massachusetts, have invented a new and 5 useful Improvement in Machinery for Drawing and Twisting Fibrous Materials; and I do hereby declare that the following is a full, clear, and exact description of the same, reference being had to the accompanying drawings, forming a part of this specification, in which—

Figure 1 is a vertical longitudinal section of a drawing and twisting machine constructed with my improvements. The section is not taken through the center of the drawing and twisting mechanism. Fig. 2 is a vertical central section of the drawing and twisting mechanism, on a larger scale. Fig. 3, is a horizontal section of the same drawn 20 on the same scale as in Fig. 1. Fig. 4 is a vertical section of one portion of the screw threaded box which contains the drawing and twisting rollers.

Similar letters of reference, in each of the 25 several figures indicate corresponding parts.

The nature of my invention consists, 1st, in the combination with the geared rollers and revolving flanged casing of a stationary box which has its inner circumference screw 30 threaded, as and for the purposes herein-after described. The advantage of placing the gear wheel outside of the casing which incloses the rollers and inside of a screw threaded box, consists in the fact that the 35 roving or sliver when broken can never get entangled with the gearing of the rollers as is frequently the case and a source of annoyance and loss of time in the usual machines where the gearing of the rollers is not 40 so protected and surrounded by a circumferentially screw threaded box, and a casing flanged at top and bottom.

It consists, 2nd, in the combination of the revolving draw head casing with a box made 45 in two parts, in order that on taking off the top of the box, the casing with the rollers and gear wheels can be got at, or removed when out of repair, while dust is effectually excluded from the roller gear wheels by having the top closed upon the box when the 50 machine is in operation.

To enable others, skilled in the art, to make and use my invention, I will proceed to describe its construction and operation.

The sliver or roving M, passes from the 55 feed rollers L, L, between and around rods X, (as represented in Fig. 1) onto the drawing or twisting device, entering the latter through the funnel b, passing between the drawing and twisting rollers A, A, and 60 through tube C, onto the spool F.

The drawing and twisting rollers A, A, have their bearings in the sides B, of a casing which has a cylindric neck b, at its top and one G, at its bottom, both necks fitting 65 into suitable holes in the top E, and bottom of a box D, E, surrounding and totally inclosing the casing. The neck b, has a funnel shaped hole through its center and the neck G, is also hollow for the purpose of allowing the sliver to pass through. The casing thus arranged is free to revolve inside of the box D, E, the necks b, G, serving as bearings. It will be observed that the top 70 and bottom plates of the casing are circular while the body of the casing is oblong. The flanges thus formed, completely over and under-hang the gearing h, h, and thus protect the same from being interfered with by broken ends of yarn.

The axle a, of one roller A, extends 80 through one side of the casing B, while the axle of the other roller extends through the opposite side of the casing. Gear wheels h, h, are attached to these axles at opposite 85 sides and outside of the casing. The cogs of these gear wheels take into a screw thread g, cut into the inside of box D, on this location of the screw-thread, hangs the novelty of my invention to a very great extent.

The upper portion of the spool frame K, is to a very great extent formed into a tube C, which fits into the hole in the neck G, of the casing. A pin I, projects from the bottom of neck G, into a recess J, in the frame 95 K, so that the revolution of the frame will cause the casing to revolve with it, while the box D, remains stationary, being fastened to the main-frame of the machine.

The revolving motion is imparted by a 100 band passing around a pulley c, attached to the lower shaft of the spool frame K. As the casing containing the rollers revolves around the vertical center line of the box D, and thus produces the necessary twisting of the sliver passing between the rollers, the latter are caused to revolve around their horizontal axes (and in directions opposite 105

to each other) by the action of the screw thread *g*, upon the gear wheels *h*, *h*, thus drawing the sliver while it is being twisted.

Several pairs of rollers each fitted to a 5 separate casing and box as described, may be employed in one machine.

I do not claim broadly a screw gear in combination with two geared rollers which draw and twist the yarn, as exhibited in the 10 patents granted to Messrs. Hazard and Peck 1856 and Messrs. Kennedy and Plummer, 1858, but—

What I do claim as my invention and desire to secure by Letters Patent, is—

15 1. The combination with the geared rollers *A*, and revolving flanged casing *B*, of a stationary box *D*, which has its inner circumference screw threaded and 20 encloses the geared rollers and casing and serves for insuring the turning of the rollers

vertically during their movement with the casing horizontally substantially as and for the purposes set forth.

2. The combination of the revolving draw head casing *B*, with a box made in two parts 25 *D*, and *E*, in order that on taking off the top of the box, the casing with the rollers and gear wheels can be got at or removed when out of repair, while dust is effectually excluded from the roller gear wheels by having the top closed upon the box when the machine is operated, substantially as set forth.

The above specification of my improvement in spinning heads signed by me this 35 13th day of April 1859.

J. E. CROWELL.
